PERRIERS-ON-ANDELLE, FRANCE

DISCHARGING APPARATUS FOR COMPRESSED GAS

Application filed September 8, 1927, Serial No. 218,270, and in France October 29, 1926.

Neutral carbon dioxide is generally known and owing to its cheapness is advantageously used in the liquid form in numerous applications. Now this gas has the great inconvenience of freezing when discharged, to such a degree as to completely obstruct the outlet openings of the containers. Consequently the delivery of the gas becomes interrupted and the bottle is put out of use during a certain time.

My invention relates to a discharging apparatus which avoids these drawbacks owing to the fact that it fulfills simultaneously the three following conditions:

15 Firstly, it prevents the impact of the compressed gas coming out from an outlet orifice upon an obstacle placed in close vicinity, such as the vulcanite or fibrous discs which are used as closure devices for the primary gas.

20 Secondly, it provides at the critical openings plugs impregnated with alcohol or any other substance having a very low freezing point only, with the object of preventing any production of ice.

25 Thirdly, it provides beyond the closing point successive chambers communicating with one another.

When the apparatus is not in use, the above mentioned chambers contain gas at one 30 and the same pressure which is that of the bottle, on the contrary when it is in service, the chambers act as pressure reducing devices which may be regulated at will for a maximum from the beginning by the manufacturer by calculating the diameter of the openings through which the receiver and the chambers communicate together or, all things being otherwise the same, by modifying the length of a middle tube controlling the path 35 that the gas is made to follow between the receiver and the first inlet opening to the chamber. According to this principle therefore, a scale of pressure reducing devices may be constructed capable of delivering any volume of gas at the required pressure without 40 risk of freezing, the system of expansion chambers located beyond the closure opening of the bottle preventing the gas from striking with freezing pressure against the various walls at the outlet.

The apparatus may be applied without any difficulty and directly to the manufacture of cheap, handy, effective and reliable fire extinguishers, these apparatus being predominantly of the kind where an interruption 55 in the operation has the most disastrous effects.

I will now describe my invention by way of example as applied to fire extinguishing apparatus, it being well understood that it 60 is not limited to this embodiment.

In this application, carbon dioxide being itself a powerful fire extinguishing medium it is not necessary to add to it as is actually the case, bulky and poisonous fire-proof compounds, the greatest obstacle which actually prevent the use of said gas by itself being the danger of freezing. The uncongealable pressure reducing device according to the present invention 65 obviates the before mentioned drawbacks as will be more fully explained hereafter by reference to the accompanying drawing which shows the preferred embodiment thereof as fire extinguisher using liquid carbon dioxide.

The appended drawing is a part longitudinal sectional view of the apparatus which comprises a strong metal cartridge 1, containing liquid carbon dioxide and in the mouthpiece of which screws a part 2 having 75 all its elements integral which is rendered air-tight by means of a plastic metal joint 3.

A screwthreaded extension 2¹ in which screws a conical nozzle is provided on part 2 inside the cartridge, the lower open end of 80 said extension opening inside the cartridge 1.

The reduced end 5 of part 4 opens in a chamber 8 formed in the extension 2¹ of part 2, and communicates by means of an eccentric passage 9 with another chamber 10 provided 85 in the top of part 2. The chamber 10 is itself in communication with the atmosphere by means of bent passages 11, 12 the latter 12 being bored in the outlet tube 13. Both chambers 8, 10 are preferably filled with a spongy material, such as tow which is impregnated with alcohol before the closing of the apparatus. The passage 11 which is situated 90 in a central hub 10¹ of chamber 10 is of confocal shape at its extremity, it is normally 95 100

closed by means of a disc 14 made of vulcanite for example acting as a diaphragm which forms a joint on the circumference of the chamber 10. In order to increase the air tightness at the circumference, the upper end surface 15 of part 2 is very closely striated with concentric grooves in which the material of the joint is crushed by the pressure of the screwthreaded cap 16 surrounding the part 2. 5 The cap 16 is provided in its middle portion with a rod 17 carrying at its end a head 18 which moves freely in a small chamber 19 and causes normally the disc 14 to engage with the tubular portion 10¹ by closing the passage 10 under the action of an outer nut 20 screwing upon a screwthreaded bearing of cap 16. The nut 20 is integral with a handle or a milled knob 21 in order to allow of lifting the parts 17, 18 and 14 and consequently the 15 required flow of gas may be controlled by the operation of said parts acting to close progressively the outlet conduit 11.

It will be readily understood that when the apparatus is not in service the pressure in the 20 chambers 8 and 10 will be the same as in the cartridge 1 but that in operation these chambers will constitute expansion chambers for the carbon dioxide passing to the delivery conduit 11 at a pressure which although it 25 cannot cause freezing is nevertheless sufficient for allowing its discharge in the fire with good results. On the other hand, the absorbing material contained in the expanding spaces added to the action of alcohol with 30 which it is impregnated will avoid all danger of freezing.

It will also be seen that the conical shape of part 4 and its outlet orifice 5 will allow of 35 regulating the conditions of the first expansion of the gas and consequently of constructing fire extinguishers in which the delivery takes place at varying pressures by simply changing the part 4. The same modifications in the result may also be effected by increasing 40 the diameter of the divers passages, it being understood that the maximum delivery provided for by the manufacturer as well as the minimum one will be controlled at will by the user on operating the parts 17, 18 and 45 14.

The apparatus constructed in the manner above described may advantageously be placed near the driver on motor vehicles for 50 instance near the steering tube the nozzle 13 being connected in that case with tubes or with a spray arranged in front of the motor in the operating zone of the fan in such a manner as to obtain the delivery of liquid carbon dioxide upon the whole of the motor 55 without letting loose the steering wheel.

It will be evident that the construction of the apparatus which has been described and illustrated is by no means limitative and that the arrangement may be modified for example as regards the number of expansion 60

chambers and their connections without departing from the principle of my invention.

It will be understood for instance that my apparatus may be applied to any type of container or bottle of liquefied or compressed 70 gas as it constitutes both a closure device for the container and a system of expansion for the gas contained in same having the aspect of a simple pressure reducing plug easy to handle, which is absolutely uncongealable at every 75 rate of delivery and the net cost of which is very much below that of any existing apparatus of this kind. When provided with the pressure reducing plug above described the bottles filled with liquid carbon dioxide or any 80 other liquefied or compressed gases may be adapted on any apparatus in which said gas is utilized as discharging or atomizing vehicle for the substances contained in same.

It will be further understood that instead 85 of alcohol, any substance having a low freezing point may be employed for impregnating the porous substance within the expansion chambers, and that in the claims where alcohol is specified, the equivalent thereof may be 90 substituted without departing from the spirit of the invention.

What I claim and desire to secure by Letters Patent of the United States is:—

1. A discharging apparatus of the character described, which comprises a compressed gas container and successive expansion devices interposed between the compressed gas container and the gas discharge orifice, and 95 plugs of porous material impregnated with 100 a liquid having a low freezing point disposed in said expansion devices at the points 105 therein which are most exposed to freezing.

2. A discharging apparatus of the character described, which comprises a compressed gas container, a body secured to the container having a passage terminating at its ends in an upper and a lower expansion chamber, and an adjustable connection between the lower chamber and the gas container, an adjustable closure device controlling the communication between the upper chamber and the discharge nozzle, and porous plugs impregnated 110 with alcohol in the expansion chambers.

3. A discharging apparatus for compressed gas comprising a body secured to a compressed gas container, a conduit in said body, lower and upper expansion chambers at both ends of said conduit, plugs impregnated with 115 alcohol in both chambers, an interchangeable nozzle having orifices and a length calculated 120 in such a manner as to connect the lower chamber with the gas container and a closure device controlling the communication between the upper chamber and the delivery 125 passage of the apparatus.

4. A discharging apparatus for compressed gas comprising a body secured to a compressed gas container, a passage in said body, lower and upper expansion chambers 130

at both ends of said passage, plugs impregnated with alcohol in said chambers, a nozzle having a shape and a length calculated to open the communication between the lower 5 expansion chamber and the gas container, a flexible diaphragm to be applied upon the orifice which opens the communication between the upper expansion chamber and the delivery conduit of the apparatus and means 10 controlling the movements of said diaphragm.

In witness whereof, I have hereunto signed my name.
